UNITED STATES PATENT OFFICE.

JOSEPH CALHOUN WATSON, OF BENTONVILLE, ARKANSAS.

NECKTIE-RETAINER.

SPECIFICATION forming part of Letters Patent No. 660,133, dated October 23, 1900.

Application filed September 25, 1899. Serial No. 731,611. (No model.)

To all whom it may concern:

Be it known that I, JOSEPH CALHOUN WATSON, a citizen of the United States, residing at Bentonville, in the county of Benton and State 5 of Arkansas, have invented a new and useful Improvement in Necktie-Retainers, of which the following is a specification.

This invention is a new and useful construction of necktie-retainer, the object being to provide an exceedingly-simple device which can be constructed from a single piece of wire and adapted to be secured upon the collar-button prior to fastening the collar thereto and which will serve to retain a 15 string or four-in-hand tie in its proper position and not only prevent it riding up, but will also prevent it slipping from side to side.

With this object in view the invention consists, essentially, in shaping a piece of wire 20 into a horizontal loop and a vertical loop, said vertical loop having an upwardly-projecting eye adapted to receive the collar-button and the horizontal loop having a depending finger formed upon the forward member thereof for 25 the purpose of preventing any lateral movement of the tie.

The invention consists also in certain details of construction and novelties of combination, all of which will be fully described 30 hereinafter, and pointed out in the claim.

In the drawings forming part of this specification, Figure 1 is a view showing the manner of using my invention in connection with a string-tie. Fig. 2 is a detail perspective 35 view of the tie-retainer. Fig. 3 is a front view. Fig. 4 is a top view.

In carrying out my invention I employ a single piece of spring-wire which is bent into an essentially rectangular-shaped horizontal 40 loop A and a vertical loop B, said loop B being arranged at the rear of the loop A and is formed with an upwardly-projecting eye C,

the lower end of which is open, as shown at C', to permit the insertion of a collar-button. The front member of the horizontal loop A is 45 formed with a depending finger D, arranged about the center thereof, said finger being preferably formed integral therewith by crimping or bending the wire, as most clearly shown in Figs. 1, 2, and 3.

In operation the retainer is secured upon the front collar-button by slipping the eye of the vertical loop over the said button. The ends of the collar are then fastened upon the button, securely holding the retainer, so that 55 the horizontal loops will project forwardly beyond the edges of the collar. The tie is then placed around the collar and the first knot tied, after which the lower end of the tie is passed through the horizontal loop and 60 arranged to the left side of the depending finger, as most clearly shown in Fig. 1. The tie is then tied in the usual manner, and inasmuch as it has been passed through the horizontal loop it will be prevented from riding up on the collar, and on account of the 65 end of the tie being arranged to one side of the depending finger it will be held in a central position and be prevented from slipping to either side.

Having thus fully described my invention, what I claim as new, and desire to secure by Letters Patent of the United States, is—

A necktie-retainer comprising a substantially-rectangular loop of wire, the rear side 75 of which is provided with an upwardly-extending bend forming an eye, the mouth of which is downward and contracted, and the front side, at its center, is provided with a depending finger.

JOSEPH CALHOUN WATSON.
